UNITED STATES PATENT OFFICE.

H. D. SEARLES, OF ROCKFORD, ILLINOIS.

GUARD-RAIL OF RAILROADS TO BE USED WITH PRONGED COW-CATCHERS.

Specification of Letters Patent No. 13,051, dated June 12, 1855.

To all whom it may concern:

Be it known that I, HOSEA D. SEARLES, of Rockford, in the county of Winnebago and State of Illinois, have invented a certain 5 new and useful Improvement in Permanent Ways of Railroads, of which the following is a full, clear, and exact description, reference being had to the accompanying drawings, which form part of this specification, 10 and in which—

Figure 1 represents a plan of a short section of the improved way, and a locomotive thereon. Fig. 2 represents a side elevation of the same, and Fig. 3 a cross section at the 15 line $\alpha\alpha$ of Fig. 1.

Many of the accidents to trains of passenger cars on railroads, which result in the loss of life, are caused by obstructions lying on the rails too low to be turned aside 20 by the cow-catcher, and on which, consequently, the locomotive will run and not infrequently be thrown off the track. It is the main purpose of my invention to prevent accidents of this kind by constructing 25 the permanent way, in such manner as will render it exceedingly difficult if not impossible for the train to run off the track, and it consists in arranging two or more guard stringers, or ribs between the rails. These 30 guards project considerably above the latter, and above the prongs of the cow-catcher so that the latter shall run between them and pass under any obstructions that may be laid across the track, thus preventing 35 the engine from being thrown off. This contrivance also tends to prevent the cars from running off the track, in case the wheels or axles of the cars should break. This contrivance has the further effect of 40 giving to the track increased stability so that trains may be run at high velocities with much greater safety than heretofore.

The bed timbers or mud sills (a), cross-ties (b) and the rails (c) as represented in the accompanying drawings, are constructed and arranged in the usual or in any convenient manner. Longitudinal stringer guard-timbers, or ribs (d) are laid and secured upon the cross-ties between the 45 rails (c); these guards run parallel to the rails and at such a distance from the same, that the wheels of the locomotive and cars will almost touch, but not rub against them; these guard ribs are of such a thickness that 50 they stand considerably higher than the rails, and are of a suitable width to insure

requisite strength and stability. Similar intermediate ribs or timbers (e) may be bolted on the cross-ties at proper distances apart, within the outer stringers; these intermediate stringers may be of the same height as, and parallel to the outer stringers. 60

By the projection of the guard ribs above the rails, sticks, branches, or other obstacles lying across the track will be held above the rails in such a position as to be caught and thrown off by the cow-catcher. In case any breakage or derangement takes place in the running gear, the cars will be held up 70 and slide along with safety on the tops of the guards instead of becoming entangled with the cross-ties as on roads of the usual construction. 75

The cow-catcher or guard which projects in front of the locomotive should be made with prongs that hang between the guard ribs, so that they would pass under a tree, or other obstacle lying on the top of the ribs, thus all liability of the cow-catcher to 80 override the obstacle is avoided, and the safety of the cars thereby greatly enhanced. The close proximity of the guard ribs to the rails render it almost impossible for the 85 wheels to get off the latter. 85

Thus it will be seen great safety is insured, either against accidental derangement or breakage of the cars, and against over-running obstacles on the track, while the strength of the track is increased. 90

The upper faces of the guard and intermediate timbers, may be wedge shaped or rounded, and many modifications of the structure and arrangement of the parts may be made without departing from the principle of my invention. 95

I am aware that several patents have been granted for central guard rails on railways and that cars have been fitted with central wheels to run on such central rails. 100

I am also aware that cars have been fitted with instruments like plowshares to remove obstructions from the rails, in front of both the side and central wheels of cars, of which Le Blank's cars, patented in France, and 105 Ashcroft's, patented in this country, are examples, but I am not aware that prior to the date of my invention, any one ever placed a series of guard ribs, elevated considerably above the rails, the entire length 110 of the track, and arranged the fingers of the cow catcher, to run between and outside of

such ribs; neither do I know that any other device the equivalent of this, for taking up and preventing cars from running over limbs of trees, or fence rails laid across the 5 track, has ever before been invented. Therefore

Having thus described my improvements in the permanent way of railroads, what I claim therein as new and desire to secure 10 by Letters Patent is—

The combination of elevated guard ribs

with the track, when the same are so arranged that the prongs of the cow-catcher of the locomotive may run between them substantially as herein set forth.

15

In testimony whereof, I have hereunto subscribed my name.

HOSEA D. SEARLES.
